CLAIM

The ornamental design for a fluid delivery device, as shown and described.

DESCRIPTION

FIG. 1 is a front right-side perspective view of a fluid delivery device showing our new design;

FIG. 2 is a front left-side perspective view thereof;

FIG. 3 is a right-side elevational view thereof;

FIG. 4 is a left-side elevational view thereof; and,

FIG. 5 is a top plan view thereof.

The broken lines illustrate structure or features that form no part of the claimed design.

1 Claim, 5 Drawing Sheets
